UNITED STATES PATENT OFFICE

98,497

DESIGN FOR A TREATMENT TUB

Charles R. Clarke, Cranston, R. I.

Application November 9, 1935, Serial No. 59,459

Term of patent 14 years

To all whom it may concern:

Be it known that I, Charles R. Clarke, a citizen of the United States and resident of Cranston, Rhode Island, in the county of Providence and State of Rhode Island, have invented a new, original, and ornamental Design for Treatment Tubs, of which the following is a specification, reference being had to the accompanying drawing, forming part thereof.

In the drawing:

Fig. 1 is a perspective view of a treatment tub showing my new design;

Fig. 2 is a plan view; and
Fig. 3 is an elevation.

I claim:

The ornamental design for a treatment tub, substantially as shown.

Signed at Providence in the county of Providence and State of Rhode Island, this 9th day of October A. D., 1935.

CHARLES R. CLARKE.
